(57) **CLAIM**

The ornamental design for a smart watch, as shown and described.

DESCRIPTION

FIG. 1 is a front view of a smart watch showing a first embodiment of our new design.

FIG. 2 is a rear view thereof.

FIG. 3 is a perspective view thereof.

FIG. 4 is a perspective view of a smart watch showing a second embodiment of our new design.

FIG. 5 is a second perspective view.

FIG. 6 is a third perspective view; and,

FIG. 7 is a fourth perspective view.

The features shown in broken lines in the drawing depict environmental subject matter and unclaimed borders and form no part of the claimed design.

1 Claim, 7 Drawing Sheets
